UNITED STATES PATENT OFFICE

WILLIAM QUICK, OF LONDON, SYDNEY EDWARD THOMAS, OF HOUNSLOW, AND
FREDERICK WILLIAM BERWICK, OF LONDON, ENGLAND

WINDOW LATCH

Application filed October 3, 1928, Serial No. 310,080, and in Great Britain November 17, 1927.

This invention relates to devices for latching or retaining windows, and particularly vehicle windows, in any desired position of adjustment.

- 5 According to the present invention, a slide-
able window construction is provided with
adjustable cam elements, mounted between
the edge or edges of a window, and guides in
which the window is slideable, and with means
10 for causing such cam elements automatically
or at will to make frictional engagement
with the guides for the purpose of securing
the window in any desired position of adjust-
ment.
- 15 According to the invention, a moveable cam
or cams carried by a window is or are urged
by resilient means into frictional securing
or latching engagement with the guides,
means being provided to render the cams in-
20 operative at will.

Reference will now be made to the accom-
panying drawing, which illustrates by way of
example a construction according to the in-
vention, and in which,

- 25 Figure 1 is a part elevation of a window
provided with adjustable cams.

Figure 2 is a sectional end elevation of the
arrangement shown in Figure 1.

- In the form illustrated in Figures 1 and 2
30 a vertically slideable window is adapted to
slide in channel shaped guides 1, whilst to
each of the vertical edges of the window 2
are fixed blocks 3 which project into the
guides 1 and constitute means for actuating
35 cam roller latch elements 4 which make fric-
tional engagement with the inner walls of
the channel shaped guides for the purpose of
securing the window in any desired position
of adjustment. The position of the cam or
40 latch 4 is controlled in the following manner.

- Through bearings 5 carried at the edge of
the window extends a rod 6 the lower end
of which abuts against a slide 7 having slots
8 through which pass studs 9 on the block 3.
45 The cam latch 4 projects through a third slot
10 in the slide 7 and the cam latch 4 is formed
or provided with a tail piece 11 which is
engaged in a V-shaped recess 12 in the block
3. Below the slide 7 is disposed a pin 13 for
50 limiting the movement of the slide, said pin

being surrounded by a coiled spring 14 for
cushioning the movement of the slide and for
normally maintaining it in a position in
which the cam or latch 4 engages the wall of
the guide 1. A second spring 15 fulfilling a 55
function similar to that of the spring 14 is
disposed between the uppermost bearing 5
and a nut 16 on the rod 6. The upper end of
this rod has an arm 17, extending therefrom
at a right angle thereto, which engages be- 60
neath the semi-circular shaped end 18 of an
operating rod 19 which extends through a
hollow metallic heading or housing 20
which encloses the upper edge of the window.
This housing is slotted at its mid portion at 65
21 to accommodate an operating lever 22 at-
tached to the centre of the rod 19.

The operation of the mechanism above de-
scribed is as follows:—

The cam roller or latch 4 is normally re-
pressed into frictional securing engagement
with the wall of the channel shaped guide 1 by
the action of the springs 14 and 15 and when
it is desired to raise or lower the window the
operating lever 22 is rocked, causing the end 75
18 of the rod 19 to assume one or other of the
positions indicated in broken lines in Fig. 2.
This operation causes the rod 6 to be de-
pressed, compressing springs 14 and 15 and
moving the slide 7 downwardly so that the 80
cam roller or latch 4 is moved further away
from the recess 12. The cam latch 4 is thereby
loosened and ceases to bind against the wall
of the guide, leaving the window free to be ad-
justed to any desired position so long as the 85
operating lever 22 is held in one or other of its
extreme positions. Immediately the operat-
ing lever is released, the springs 14 and 15 be-
come operative, and restore the parts to
normal position, the slide 7 moving the cam 90
roller 4 upwards until its tail piece 11 is re-
engaged by the converging walls of re-
cess 12 to force the cam roller to engage the
wall of the guide and secure or latch the
window against movement. 95

In practice, and as applied to automobile
vehicle windows it is preferred to employ two
cams at each side of the window, and to use
the invention in conjunction with a spring
balanced arrangement which cushions down- 100

ward movement of the window and assists the upward movement.

We claim:

1. In combination with a member to be latched, a guideway in which said member is slidable, a block carried by said member and having a substantially V-shaped recess directed toward said guideway, a slide longitudinally shiftable between said block and said guideway and having an aperture normally positioned opposite said recess, a latching member mounted in said aperture and normally engaging said guideway, said latching member having a nose normally positioned in the apex of said recess, a rockshaft extending transversely of the member to be latched, and means operable by rocking said rockshaft in either direction from shifting said slide relatively to said block and releasing said latching member.
2. An apparatus according to claim 1 including yieldable means normally maintaining the slide in position with the nose of the latching member in the apex of the recess of the block and wherein the means operable by the rockshaft for releasing the latching member comprises a cam carried by the rockshaft and a longitudinally shiftable rod between said cam and the slide.
3. In combination with a guideway member, a closure member slidable in said guideway member, latching means carried by one of said members and adapted to frictionally engage the other member and secure said closure member against movement, means normally urging said latching means into engaging position and means for releasing said latching means, said last-named means including a shaft mounted to rock on an axis parallel to said slidable closure and a cam carried by said shaft and operable by the rocking movement of said shaft in either direction.

In witness whereof we affix our signatures:—

45
